UNITED STATES PATENT OFFICE

EDGAR WILLIAM BRANDT, OF PARIS, FRANCE

DEVICE UTILIZABLE FOR CAMOUFLAGE AND THE LIKE

Application filed September 14, 1929, Serial No. 392,710, and in France September 14, 1928.

The present invention relates to devices adapted to disguise or camouflage any object whatever on the ground, especially military objectives, hunters, etc.

The invention has chiefly for its object to provide screens which, though completely disguising the objects, the presence of which must not be revealed, are themselves imperceptible to the observer even at a short distance or with the help of field glasses.

An important feature of the invention resides in that said screens consist of an invisible (transparent or tenuous) support, on which are disposed zones of various opacity, 15 preferably edged by broken irregular lines, in order to avoid any distinct or geometrical outlines which would reveal the presence of the screen; in the case that these screens are made of paper, fabrics or the like, great attention must be paid to their absolute tension to 20 avoid any folds or corrugations which would produce straight lines across the screen, thus revealing its presence.

The screen has preferably a very little 25 thickness the better to ensure its invisibility; finally it is coloured in suitable colours to blend with the neighbouring objects; the zones of various colours are themselves edged by broken lines, the latter intermingling or 30 not with the lines delimiting the zones of various opacity.

According to a preferred embodiment of the invention, the screen is provided with several movable elements, so that an easy 35 change of their respective inclination may be obtained.

The various embodiments of the invention, hereafter illustrated and described, satisfy more particularly the required conditions of 40 excessive lightness, easy handling and possibility of folding under handy dimensions in order to facilitate the transport, which conditions are of great importance where military contrivances are concerned.

Further characteristics of the invention, especially relating to methods or devices allowing to change the shade or aspect of the screen, as well as various practical embodiments of the invention, varying according to 45 their application, will be described in the

following specification with reference to the appended drawings which are given solely by way of example.

In these drawings:

Figs. 1 and 2 show, by way of example, a 55 screen according to the invention with two different methods for distributing the more or less opaque zones on the invisible background or supporting frame.

Fig. 3 shows a screen for the camouflage of an objective in a plain.

Fig. 4 shows a screen for the camouflage of a battery of two cannons, machine guns or the like.

The screen shown in Fig. 1 comprises a supporting-frame or background 1 consisting of a network or fabric of large meshes thus providing an invisible (transparent or tenuous) support, on which a gauze-work of somewhat closer meshes 2 is applied, forming a more or less opaque zone bordered by a broken line 3, the configuration of which is very contorted; the opaque spots 2 are distributed in such a way that, as a whole, they form pieces, which radiate in a general direction from the centre outwards. A more opaque layer of tissue, paper etc. 4 is superimposed on the central part of this screen, and similarly bordered with broken lines. Said broken outlines, separating the various zones of different opacity from one another can intermingle on given points with the result that certain parts of the most opaque fabric 4 can spread over the less opaque zone 1.

Fig. 2 shows a variation of this device, in 85 which the screen is composed of a net-work 1 and an opaque fabric 5 provided with holes 6, 7; said holes can even pierce the net 1. Pieces 11, 12 of tissue 5 or of a more opaque fabric 13, 14 are scattered on rationally chosen 90 points of the screen; some of these pieces may have holes 15, 16, piercing the whole screen, or only certain layers of fabric; these supplementary pieces, as well as the different holes are themselves surrounded by broken 95 lines.

In practice, the screen must be very tightly stretched, so that all folds or corrugations are avoided and, as shown in Fig. 3 by way of example, it will be supported by a folding 100

frame-work (as below described) making it possible to obtain a perfect tension of the superimposed fabrics or like layers.

As a general rule, the successive layers of net-work, fabric, paper or the like are superimposed in order to increase the opacity from the periphery towards the centre; moreover, in the illustrated example, this progression of the opacity is regularly realized; even outer regions may preferably show local opaque spots without the whole element losing its described general characteristic, that is to say, the centre will always be more opaque than the outer zones. The term "centre" must however here be given a very wide meaning; it must not necessarily be confused with the geometrical centre of the exposed surface, but is preferably situated in front of the objective or parts of it, the shade (or mobility) of which contrasts most with the neighbouring background; one given screen can therefore have several centres of opacity if the objective itself is manifold. This is the case illustrated in Fig. 4, which shows diagrammatically a screen for a battery of two infantry cannon of the Stokes-Brandt type.

The invisibility of the screen itself depends to a great extent on its shade and distribution of the light and dark zones; said distribution may be independent of the distribution of the more or less opaque layers of tissue. According to a preferred embodiment of the invention, the various screen zones of different colours are horizontally disposed and alternate, in light and dark disposition; they are also preferably bordered by broken lines, as described for the fabric layers; light green or yellow zones alternating with dark brown or green zones are preferred; furthermore, the screen itself may be made of fabrics having these colours.

The screens thus realized are invisible at short distances on almost any ground, and experience has shown that it is almost impossible to distinguish them from the neighbouring scenery.

The lower border of the screen (Fig. 3) mingles with the neighbouring ground and is quite imperceptible to the eye; the outer part of the screen, which is less opaque, allows partial view of the background of the field, so that the whole screen blends with it. A number of holes of the central opaque part and the isolated and differently coloured opaque spots sometimes appear light, others appear dark, thereby increasing the desired effect of invisibility.

According to a modified form of construction, the screen might likewise be mounted in such a way as to render it possible to modify, at will, its aspect, while in use, according to the face and the angle under which each element is illuminated or seen by the observer, and thus be exactly adapted to the aspect of the neighbouring ground, in spite of the act-

ual variation or aspect of the latter. More particularly certain elements might be placed within the cone of shadow of one or several supplementary elements, which would themselves be illuminated by the sun or artificially at different or variable intensities. 70

Other screens with manifold elements would obviously be imagined, pivoting the one upon the others so that their relative positions could easily be modified in any desired direction by sliding, pivoting or any other convenient movement. 75

In order to enlarge the field of coloration effects of the screen, these may likewise be illuminated either from behind or in the front by means of beams of light rays conveniently reflected and, if necessary, diffused by any convenient device and, if necessary adapted to follow the apparent course of the sun. 80

A course of artificial light may likewise be utilized and the trajectory of the light rays interrupted by convenient coloured panels. 85

In practice, the screens according to the invention are to be made of any convenient materials, such as fabrics, paper, cellophany or other cellulosic compounds either transparent, translucent or opaque, allowing economically to provide very light elements, which are most suitable for the various coloration processes. The screens are preferably coloured on both sides. If the material composing the screen is itself sufficiently rigid, no support is needed. On the other hand, this material may artificially be rendered rigid, for example by means of wire-netting embedded in the material. 90

In general, the screen itself will be supported by a detachable frame-work preferably formed of pivoted or dismountable elements, in order to occupy the smallest possible space during the transport. Under working conditions, the whole apparatus must be very thin and the framework disguised or rendered invisible by the screen itself and more especially by the most opaque parts. 95

Some preferred embodiments of such frames are hereinafter indicated by way of example; the screen shown in Fig. 3 has a frame-work comprising arms 111, 112, 113 pivoted at point 114; when the screen is fully open, the arms 113 are automatically locked by spring latches. 100

According to the invention, the screens may likewise be constituted so as to provide for a rapid passing from one tonality to the other. For this purpose, the panels might be formed by a series of elements in the form of sections, coloured differently on their two faces and dependent on control devices to show at will one or the other of their faces to the observer. 105

Against the vertical or oblique observa- 110

tion by aeroplanes, the arrangement shown in Figs. 1 and 2 will successfully be used. The outer part of the net is cut out along a distorted outline; at various points, it is hooked up on steel wires, attached for example to neighbouring trees or to posts strengthened by anchoring devices etc.

5 The present invention is naturally not limited to the above described and illustrated 10 devices but is susceptible to any modifications necessary according to circumstances and requirements.

Having now fully described and ascertained my said invention and the manner 15 in which it is to be performed, I declare that what I claim is:—

20 1. A screen adapted for camouflage and like uses, comprising zones of various opacity and so disposed that the opacity is diminishing towards the outline of said screen.

25 2. A screen for camouflage and like usage comprising zones of various opacity, wherein said zones of various opacity are edged by frequently broken lines and irregularly distributed on said screen, some smaller zones of lesser opacity being situated on larger zones of higher opacity.

30 3. A screen for camouflage and like usage comprising zones of various opacity, wherein said zones of various opacity are edged by frequently broken lines and irregularly distributed on said screen, some smaller zones of higher opacity being situated on larger zones of lesser opacity.

35 4. A screen for camouflage and like usage comprising zones of various opacity, wherein the size and number of the more opaque parts respectively decrease towards the exterior, whilst the size and number of the less opaque 40 parts decrease towards the centre.

45 5. In a screen for camouflage and like usage comprising zones of various opacity, the further feature residing in said screen is coloured with horizontally disposed zones, alternatively light and dark.

50 6. A screen for camouflage and like usage comprising zones of varying opacity, wherein said zones are colored alternately light and dark, and are edged by broken lines.

EDGAR WILLIAM BRANDT.
